DOORLOCK

Karl S. Geiselhart, San Jose, Calif.

Application October 29, 1934, Serial No. 750,477

1 Claim. (Cl. 292—62)

The present invention relates particularly to locking means for sliding doors such as double doors for garages and other buildings, cabinets, show-cases, etc.

5 It is one object of the present invention to provide a locking means of the character indicated whereby a latch and locking means are disposed and arranged to cooperate with a handle on one of a pair of doors to effect the fastening of 10 the two together.

It is another object to provide a means of the character indicated wherein the latch and locking parts are moved into and out of their locking positions simultaneously and entirely by manipulation of the handle.

15 It is a further object of the invention to provide a device of the character indicated that will be economical to manufacture, simple in form and construction, that consists of few parts, that 20 will be easy and positive in operation, and that will be strong, durable, and highly efficient in its practical application.

The drawing is a perspective view of a device 25 embodying my invention and operatively mounted upon a pair of doors, partly in section and with parts broken away.

30 Referring now more particularly to the drawing, 1 and 2 indicate two sliding doors that have moved into a closed position so as to overlap at their meeting edges as at 3, portions of the top guideways being indicated at 4.

Considering door 2 as the rear door, a keeper plate is mounted on the forward surface thereof as at 5, and this plate is provided with an opening 6 including a radially disposed notch 7, the door itself being hollowed out back of the plate to form a pocket at 8.

35 The door 1 is bored through as at 9 in axial alignment with the opening 6 when the doors are closed, the inner side of the door 1 being provided with a recess at 10 fitted with a plate 11 which in turn is provided with a bearing 12 for a bolt 13.

The outer face of door 1 is fitted with a fixed plate 14 provided with a bearing 15 for the enlarged end 16 of the bolt 13.

40 The bolt 13 has a head 17 mounted on its inner end, which head is adapted to pass through the opening 6 and provided with a finger 18 movable through the notch 7 and engageable with the back of plate 5. A spring 19 is inserted between plate 11 and shoulder 20 on end 16 to urge head 17 into the recess 10.

45 On the lower end of plate 14 is formed a boss 21 having its inner edge 22 approaching the center of the plate and disposed at right angles thereto, and its top edge 23 angularly disposed relative thereto as shown. An upstanding eye is mounted on boss 21 as at 24 with its inner side flush with the edge 22.

50 At 25 is shown a plate having substantially the

same dimensions as the plate 14 and overlying the same, but with a recess formed in its lower portion as at 26 complementary to the boss 21. This end of plate 25 has an upstanding eye as 27 mounted thereon with its inner surface flush with the inner edge 28 of recess 26 and adapted to align with the eye 24 when the device is in a locking position.

55 The plate 25 is mounted on end 16 of bolt 13 as shown at 29 and forms an integral part of the 10 bolt to turn as a unit therewith. The point at which the plate 25 is mounted on the bolt 13 is so disposed that an extension of the axis of the bolt would pass through substantially the center of the handle 30 which is mounted on the plate 15 25 and forms a part thereof.

When the parts are in a locking position as shown in the drawing and above described a padlock as 31 may be passed through eyes 24 and 27, thereby securing the plate 25 against rotation 20 relative to plate 14 and locking the two doors securely together.

In unlocking the doors the padlock is, of course, removed, and the plate 25 is then rotated to the 25 position indicated by the dotted line 32 through the medium of handle 30. When the finger 18 reaches notch 7 the spring 19 draws it into the recess 10 and the doors are free to slide past each other.

30 In locking the doors they are first moved into the position indicated through the medium of handle 30 which, as stated above, lies in the position indicated by the dotted line 32. When the proper positioning is attained a little pressure 35 on the handle 30 overcomes the resistance of the spring 19 and the parts 17, 18 are thrust through opening 6, and the handle is turned to the final closed and locking position.

It is to be understood, of course, that while I 40 have herein shown and described but one specific embodiment of the invention, changes in form, construction, and method of assembly and operation may be made within the scope of the 45 appended claim.

I claim:

In a door lock, a plate adapted to be fixedly mounted on the outside of a door and having an upstanding part provided with an eye disposed on one end thereof, a locking bolt slidably and rotatably mounted in said plate, a second plate mounted on said bolt as an integrant part thereof to overlie the first plate and having an upstanding part disposed thereon provided with an eye 55 alignable with the eye on the first plate, and a handle disposed on the second plate as an integrant part thereof whereby the axis of rotation of the handle coincides with the axis of rotation of the bolt.

KARL S. GEISELHART. 60
